UNITED STATES PATENT OFFICE.

JACOB S. JAMMER, OF NEW YORK, N. Y., ASSIGNOR TO WESTERN ELECTRIC COMPANY, INCORPORATED, OF NEW YORK, N. Y., A CORPORATION OF NEW YORK.

CARRIER-WAVE TRANSMISSION.

Application filed July 17, 1923. Serial No. 652,031.

This invention relates to carrier wave transmission.

Among the objects of the invention are:

5 To provide a multiplex carrier wave system wherein a high degree of selectivity is obtained with a relatively small amount of apparatus.

To provide an efficient repeater which is inexpensive to manufacture and maintain.

10 To provide a repeater whose gain is substantially independent of changing conditions of the line with which it is associated.

To provide a two-way repeater whose gain is substantially independent of changes in 15 the impedance characteristics of the transmission line sections coupled thereto.

To provide a two-way repeater which may be coupled to a transmission line without employing hybrid coils, balancing networks 20 or directional filters.

To provide a repeater whose gain is independent of the frequency of the currents to be amplified thereby.

25 To provide a repeater whose gain is substantially constant over a wide range of frequencies.

In accordance with one feature of the invention, a multiplex carrier current telephone system, wherein different carrier frequencies are employed for the various channels and the same carrier frequency is employed for the oppositely directed transmissions over the same channel, has at each terminal an artificial line or network individual to each channel for balancing the main line over a frequency range equivalent to one side band only of the carrier.

In accordance with another feature of this invention, a carrier current telephone or other signaling system is provided with a 40 two-way repeater having one or more amplifiers connected in a loop circuit which is coupled to the transmission line without employing hybrid coils, balancing networks 45 or directional filters.

In the drawing:

Fig. 1 shows diagrammatically a multiplex carrier current telephone system provided with a mid-line repeater having amplifiers whose input and output circuits are 50 inductively coupled in a loop circuit.

Fig. 2 shows diagrammatically a repeater whose input and output circuits may be connected directly to the main transmission line.

Fig. 3 shows gain characteristic curves for 55 the repeater.

Fig. 1 will first be described.

The multiplex carrier current telephone system of Fig. 1 comprises a main line ML extending between terminal stations W and E at each of which is located apparatus and circuits for connecting low frequency lines to the respective carrier current channels. Where the geographical distance between terminal stations is sufficient to require it, 65 one or more mid-line repeaters R are connected to the transmission line ML.

The apparatus and circuits at the two terminal stations are similar so that apparatus and circuits for connecting only one low 70 frequency line to a carrier current channel will be described, and whenever any distinctions appear they will be particularly pointed out.

The system disclosed has four channels, 75 each operating with carrier current of a different frequency. The oppositely directed transmissions over the same channel employ the same carrier frequency. Only one side band of frequencies is transmitted, the same 80 side band of frequencies being transmitted in both directions.

The channel frequencies are separated at the terminal station by band filters BF₁, BF₂, BF₃ and BF₄ which may be of the type 85 disclosed in U. S. patent to Campbell No. 1,227,113, May 22, 1917. Each band filter is designed to pass only currents of frequencies within the particular side band being transmitted over the channel with which the filter 90 is associated, and to suppress currents of all other frequencies.

Low frequency line L₁, extending to and terminating at a telephone switchboard (not shown), is coupled to the high frequency 95 main line ML by means of transmitting and receiving channels TC₁ and RC₁ connected to line L₁ through a balanced transformer 1 and the main line ML through a balanced transformer 2.

The two channels TC₁ and RC₁ are rendered substantially conjugate by the provi-

sion of artificial lines or nets LN_1 and MLN_1 to balance the respective low frequency and high frequency lines. The net MLN_1 merely balances the high frequency line for the par-

5 ticular range of frequencies transmitted and received by the channels TC_1 and RC_1 .

The transmitting channel TC_1 includes a modulator M_1 which may be of any well known type, such, for example, as the electronic valve modulator disclosed in Fig. 42 of the article on "Carrier current telephony and telegraphy" by Colpitts and Blackwell appearing in "Transactions of American Institute of Electrical Engineers", volume 40, 15 1921.

Carrier currents of the frequency assigned to the channel are supplied to the Modulator M_1 from a carrier current source CS .

The receiving channel RC_1 includes a low 20 pass filter LPF_1 and a demodulator DM_1 .

The low pass filter LPF_1 is of the type disclosed in the Campbell patent, supra. It is designed to pass currents of frequencies below the carrier frequency assigned to the 25 channel and to suppress currents of higher frequencies.

The low pass filter LPF_1 therefore serves to prevent the circulation, in the loop circuit including the conjugately related transmitting and receiving channels TC_1 and RC_1 , of currents of frequencies not balanced by the network MLN_1 .

The demodulator DM_1 may be of any well known type, such, for example, as the electronic valve demodulator disclosed in Fig. 42 of the Colpitts and Blackwell article, supra. Carrier currents are supplied to the demodulator DM_1 from the source CS .

It will be noted that in the multiplex carrier current telephone system of Fig. 1 only two band filters for each channel, one at each terminal station, are required. Since each high frequency main line balancing network is required to balance for only the frequencies within the range of one side band, these networks are less expensive to manufacture and maintain. Furthermore, since only one side band of frequencies is transmitted in both directions over a channel, greater frequency spacing of the channels results for a given carrier spacing thereby affording greater selectivity. Consequently the band filters may be made less expensive as the frequencies against which each is required to discriminate are spaced farther away from those which are to be passed therethrough.

The two-way repeater of Fig. 1 comprises an electronic amplifier A of the usual three electrode type having an input transformer 3 and an output transformer 4. The secondary winding of the output transformer 4 is connected through a resistance network 5 to the primary winding of the input transformer 3 by means of conductors 6 and 7.

Thus, the amplifier is included in a loop circuit which is connected to the transmission line ML by means of conductors 8 and 9.

The resistance network 5 is adjusted to 70 such a value that the loss within the loop plus the amplified energy fed to the transmission line by way of the connecting conductors 8 and 9 exceeds the total gain or amplification of amplifier A . The total 75 gain or amplification is the initial amplification plus the successive re-amplifications due to a portion of the amplifier output energy being fed back to the input of the amplifier. When the resistance network is so adjusted that the repeater can not sing, the amount by which the loss exceeds the gain may be termed the "singing margin" 80 of the repeater. Thus "singing margin" 85 may be defined as the difference between the total loop gain for a given condition and that loop gain which will just cause the repeater to sing. The various elements of the loop circuit should be adjusted so that the initial input energy to the amplifier 90 and the amplified energy fed back from the output thereof are substantially in phase.

It has been demonstrated experimentally and proved mathematically that in a repeater of the character shown in Fig. 1, the 95 total gain thereof is substantially independent of the absolute gain of its amplifier and is a function of the singing margin. The total gain to be obtained from the repeater can therefore be regulated by varying the 100 values of the resistance network in the loop circuit.

The total gain Q of the repeater may be expressed by the equation

$$Q = \frac{K\sqrt{M}}{M-1}$$

105

where M is an index of the singing margin and K is a constant whose value determines the stability of the repeater gain. The constant K is a function of the ratio of the repeater input impedance to the impedance of the transmission line to which the repeater is connected.

The net gain of the repeater can be stabilized to a considerable extent throughout its working range by increasing the ratio of the repeater input impedance to the line impedance.

The gain characteristic of the repeater is shown in Fig. 3 wherein for different values of K curves have been plotted with the gain of the repeater in standard cable miles as ordinates and singing margin in standard cable miles as abscissæ.

These curves show that the gain of the repeater is very unstable for very low values of K and is rather stable as K approaches the limiting value of 2. When K equals 2 the ratio of the repeater input impedance to

110

115

120

125

130

the line impedance is infinite and no net gain is derived from the repeater; consequently the curve for $K=2$ is shown in dotted lines.

5 When the input impedance of the repeater is either high or low as compared to the impedance of the line, small changes in the line impedance have relatively little effect upon the gain to be derived from the repeater so that the repeater is very stable.

In order that the repeater may be rendered stable, it is desirable that the input impedance of the input transformer 3 be made high as compared to the impedance of 15 the transmission line.

This may be accomplished by employing as the input transformer a step down transformer whose input impedance, of course, does not match the impedance of the line.

20 Similar results can, of course, be obtained by employing a step up input transformer whose input impedance is low as compared to the line impedance, but the step down input transformer is preferred.

25 Since the repeater gain is substantially independent of changes in line impedance, the repeater may be employed for two way operation and connected to the line without employing the usual hybrid coils and balancing networks. Furthermore in multiplex carrier signaling systems it is not necessary to employ the usual directional filters to separate the oppositely directed transmissions at the repeater.

35 Obviously the repeater may be employed in systems wherein the number of channels are more or less than that shown in Fig. 1.

The repeater of Fig. 2 is similar to that of Fig. 1 but differs therefrom principally 40 in that capacitative instead of inductive couplings are employed in its input and output circuits.

This repeater comprises an electronic amplifier A of the usual three electrode type 45 having in its input circuit series coupling condensers 10 and 11, the variable resistance network 5, and a shunt resistance 12 and in its output circuit series coupling condensers 13 and 14.

50 The coupling condensers should be of large capacity so as to have as low a capacitative reactance as possible.

The repeater may be associated with the transmission line ML by connecting the input circuit conductors 15 and 16 and the output circuit conductors 17 and 18 directly thereto with conductors 15 and 18 connected to one line conductor and conductors 16 and 17 to the other line conductor. When so 65 connected, the amplifier of the repeater is included in a loop circuit which includes as a portion thereof a very short length of the line conductors. The repeater of Fig. 2 when connected to the transmission line in 80 this manner functions, in the manner ex-

plained in connection with the repeater of Fig. 1, to amplify energy incoming thereto from either direction over the transmission line.

The invention set forth herein is of course 70 susceptible of various other modifications and adaptations.

The invention claimed is:

1. In a signaling system including a transmission line, the method of employing a one 75 way repeater for two way operation which comprises impressing part of the amplified energy upon the transmission line, impressing the energy received from the transmission line and another part of the amplified 80 energy on the input of the repeater to control the amplification of the received energy, and attenuating the energy impressed on the input sufficiently to prevent singing while amplifying the received energy.

2. In a signaling system including a transmission line, the method of employing a one way repeater for two way operation which comprises absorbing between the point of 90 connection of the output of the repeater to the transmission line and the input side of the repeater only such an amount of the transmitted energy as will prevent the generation of oscillations while amplifying the 95 energy transmitted to the repeater.

3. In a signaling system, a transmission line over which signaling currents are transmitted in opposite directions, and a repeater having input and output circuits included 100 in a loop circuit associated with said transmission line, said repeater having an input impedance which differs by a considerable amount from the impedance of the line.

4. In a signaling system, a transmission 105 line over which signaling currents are transmitted in opposite directions, and a repeater having input and output circuits included in a loop circuit associated with said transmission line, said repeater having an input impedance greater than the impedance of 110 the line.

5. In a signaling system, a transmission line extending between geographically separated stations and over which signals are 115 to be transmitted in opposite directions, and means located at an intermediate point along the transmission line for amplifying signals transmitted in either direction, said means comprising an electronic amplifier having 120 an input circuit and an output circuit, an energy feed back coupling from the output to the input circuits whereby the fed back energy is insufficient to cause the amplifier to generate oscillations, said input circuit being coupled to the transmission line and having therein an input transformer whose input impedance differs very materially 125 from the impedance of the line.

6. In a signaling system, a transmission 130

line extending between geographically separated stations and over which signals are to be transmitted in opposite directions, and means located at an intermediate point 5 along the transmission line for amplifying signals transmitted in either direction, said means comprising an electronic amplifier having an input circuit and an output circuit, an energy feed back coupling from the output to the input circuits whereby the fed back energy is insufficient to cause the amplifier to generate oscillations, said input circuit being coupled to the transmission line and having therein a step down transformer 10 whose input impedance is high as compared to the impedance of the line.

7. A signaling system having in combination a transmission line extending between geographically separated stations over 20 which signals are to be transmitted in opposite directions and means located at an intermediate point along the transmission line for amplifying the transmitted signals, said means comprising an electronic valve having an input circuit and an output circuit, coupling means for feeding energy from the output circuit back to the input circuit less than the amount necessary to generate sustained oscillations, and means for connecting 25 the input and output circuits in shunt of the transmission line.

8. In a carrier current system, a high frequency line, a plurality of detectors connected thereto, a balancing network individual to each detector for balancing the high frequency line at a given range of frequencies corresponding in width to that of 35 only one side band of frequencies, an individual band filter connecting each detector and the associated balancing network to the high frequency line, a modulator associated 40 with each detector, and a low pass filter associated with each modulator and detector to

prevent singing at frequencies not balanced by the network.

9. In a multiplex telephone system, a high frequency line for carrying high frequency currents of different frequencies each modulated in accordance with speech; a plurality of band filters, of respectively different frequency transmission ranges each range corresponding in width to that of essential speech frequencies, directly connected to the line; an individual net circuit associated with each band filter for balancing the line for a range of frequencies corresponding in width to only one side band of frequencies transmitted by its associated band filter; telephone modulating and detecting means connected between each filter and its associated net circuit; and an individual low pass filter associated with each modulating and detecting means to prevent singing at frequencies not balanced by the network.

10. In a multiplex telephone system, a high frequency line for carrying high frequency currents of different frequencies each modulated in accordance with speech; a plurality of band filters, of respectively different frequency transmission ranges each range corresponding in width to that of essential speech frequencies, connected to the line; an individual net circuit associated with each band filter for balancing the line 75 for the range of frequencies transmitted by its associated band filter; telephone modulating and detecting means connected between each filter and its associated net circuit; and an individual low pass filter associated with 80 the modulating and detecting means to prevent singing at frequencies not balanced by the net circuits.

In witness whereof, I hereunto subscribe my name this 11 day of July A. D., 1923.

JACOB S. JAMMER.
